REFRIGERATED FREIGHT VEHICLE

James J. Chiardio, Philadelphia, Pa.

Application January 11, 1940, Serial No. 313,311

5 Claims. (Cl. 62—19)

The object of the invention is to provide improvements in refrigerator cars broadly, and especially in those which are sub-divided into a plurality of compartments.

Another and more specific object is to provide a car of this class, in which the several compartments are strictly independent of one another, so far as they may be loaded and unloaded at will and without disturbing the contents of the remaining one or more compartments, but are so inter-connected by air ducts with their respective end and intermediate ice bunkers, or equivalent sources of "cold," that a remarkably uniform degree both of temperature and humidity is maintained throughout the car as a whole, thereby entirely eliminating so-called black rot, mildew, mold and similar forms of objectionable contaminating and destructive media.

A further and more specific object is to provide a car of this type, in which there are provided the usual end ice bunkers and in addition thereto at least one more centrally located bunker, it being understood that one such additional bunker may be located in the exact center, or spaced to one side thereof in order to provide compartments of different capacities, or a plurality of such additional bunkers may be employed, but in any case there are provided apertures in the upper and lower portions of the bunker walls for the relatively free circulation of the air within the car.

There is also preferably provided a false inner flooring of slats, upon which the basket, box, barrel or other contents of the respective compartments rest, said inner flooring being spaced well above the floor of the car, and adapted to receive cracked ice both prior to the initial loading operation, and also to receive the cracked ice that eventually falls from above the packages, as the latter are unloaded in whole or in part from each of said compartments, following which the presence of such ice still further contributes to the low temperature of the interior of the car.

In addition to the foregoing, there is provided a system of drains for leading the water of the melting ice from the ice bunkers and also from the intervening storage spaces towards the exterior of the car, while the several discharge outlets of such drainage system are effectively closed by means of traps, against the intake of hot air from immediately above the railway tracks upon which the car is mounted.

With the objects thus briefly stated, the invention comprises further details of construction and operation, which are hereinafter fully brought out in the following description, when

read in conjunction with the accompanying drawing, in which Fig. I is a vertical, longitudinal sectional view of a car comprising one embodiment of the invention; Fig. II is a vertical section on the line II—II of Fig. I; and Fig. III is a horizontal section on the line III—III of Fig. I.

Referring to the drawing, the refrigerator car is shown as comprising a floor 1, resting upon longitudinal trusses 2, in turn supported by the usual trucks 3, and provided with the usual coupling devices 4 for operatively connecting said car in a train. From the transversely opposite edges of said floor rise side walls 5 through each of which extend a plurality of doorways 6, normally closed by any desired type of door 7, while the adjacent ends of said side walls are connected by upwardly extending end walls 8. Finally, the upper edge portions of said side and end walls are spanned by a top wall or roof 9, which may be of any desired cross section, such for instance as that shown in Figs. I and II.

Within said car and spaced from the end walls 8 are vertically extending partitions 10, providing between them and the respective end walls bunkers 11 in which cakes of ice 12 are stored, access to said bunkers being through one or more apertures of filling ports 13 in the said roof, surrounded by flanges 14 and adapted to be spanned in warm weather by removable and angularly adjustable closures 15. The lower portion of each of said bunkers is provided with a removable false floor 16, formed of spaced slats upon which the blocks of ice 12 directly rest, while each of said bunker partitions is provided with a set of apertures comprising air inlets 17 adjacent to the roof of the car, a second set of apertures comprising air outlets 18 adjacent to the bottom of the car but above the false bunker flooring 16, and preferably also a third set of apertures 19 beneath the level of the slatted flooring, each group of apertures being for a purpose hereinafter described.

Located at any desired position within said car and spaced from and between the bunker partitions 10 is a third bunker 20, defined by and between spaced bunker walls 21 and adapted to normally contain blocks of ice 22. This third bunker is deemed sufficient to illustrate the principles of operation herein involved, but is intended to represent any desired number of bunkers in addition to those positioned at the ends of the car. This third bunker space, like those first mentioned, is similarly provided with a false slatted flooring 23 spaced above the floor 1 of the car,

while the partitions 21 are provided in each case with at least three sets of apertures 24, 25 and 26, corresponding with the apertures 17, 18 and 19, respectively, in the first mentioned bunker partitions 10. On the other hand, if desired each pair of partition apertures 18 and 19 in the partitions 10 and each pair of similar partitions 25 and 26 in the partitions 21 may, if desired, comprise vertically enlarged apertures which extend both above and below the false slatted flooring 16 and 23 within said bunker compartments.

This central or intermediate bunker 20, like those located at the ends of the car, is provided with one or more openings 20a extending through the roof of the car for the purpose of loading cakes of ice into this bunker, and each such opening is adapted to be entirely or partially closed by means of an adjustable, demountable closure 20b.

Within said car and upon the opposite sides of the intermediate bunker 20 are storage spaces 27, which are accessible entirely independently of one another through the doorways 6, upon the opposite sides of the car and leading into each of said spaces respectively. Within the lower part of each storage space a false flooring 28 of spaced slats is provided, preferably in substantial alignment with the corresponding slatted floorings of the respective ice bunkers, each of said floorings, both for storage spaces and bunkers being removable at will for the purpose of cleaning beneath them, and when in operative position being spaced from about 4" to 6" above the upper surface of the car floor 1. As indicated in Fig. I of the drawing, the several storage spaces within the car may be filled either partially or entirely with either the same or entirely different commodities, which for purposes of illustration, are here represented as comprising goods contained in baskets 29 in one compartment and in boxes or crates 30 in the other compartment. These baskets, boxes, crates, or other form of containers may be packed either in spaced relation, as indicated in the left hand compartment, or may be packed closely together, as indicated in the right hand space. In either arrangement loose, broken or cracked ice 31 may be thrown loosely over the top of the containers when closely packed, or both over the top and between the several containers when loosely packed. In addition, smaller particles of cracked ice may be initially placed beneath the slatted flooring, as also indicated in Fig. I, or may be initially omitted from this latter location as desired.

In the operation of a car of this type, the same may be loaded in each of its storage spaces at a single location, or one storage space may be loaded at one place and the car then shifted to another place before the other of the said storage spaces is loaded. In any such case, it is well recognized that the fruit, vegetables, or the like placed within the car are characterized by a considerable degree of so-called field or ground heat. It is for the elimination of this initial heat that the ice 31 is frequently thrown over and about the containers 29 and 30, and during the elimination of such heat most of this ice melts, but in the meantime the temperature both of the containers with their contents, and the surrounding atmosphere of the storage space will have been lowered to the desired degree, at which the particular perishable commodities being transported will be preserved, for at least a sufficient time to permit them to be carried from

their place of origin to the particular metropolitan center or centers, where they are unpacked from the car and from which they are distributed to the various dispensing agencies. Having once lowered the temperature within each storage space, the ice blocks within the bunkers 11 and 20 will tend to insure the maintenance of the desired low temperature for a considerably greater period. Furthermore, by positioning an additional one or more ice bunkers intermediate of the ends of the car, and interconnecting such additional bunker in the air circulating system of the car, the heretofore objectionable and in fact ruinous black rot of certain perishable fruits and vegetables is entirely eliminated.

In addition to the foregoing, it is to be noted that the natural circulation of air through bunkers and storage spaces is maintained to a far greater degree than in the absence of the intermediate bunker 20. In fact, in refrigerator cars of present-day construction, the center of the car is so remote from the ice bunkers at its opposite ends, that the air at such central point remains practically static, thus in time absorbing heat and permitting a substantial rise in temperature of the products in the center of the car, and simultaneously tending to encourage the growth of mildew, mold and such objectionable developments and growths. Furthermore, relatively warm air rising within a given storage space, if unable to flow freely into the adjacent end compartment 11 by way of the upper aperture 17, and thence downwardly past the ice 12 and again into said storage space by way of either or both of the apertures 18 and 19, or their equivalent vertically enlarged aperture, will be enabled to flow into the intermediate bunker 20 through the upper aperture 24, and upon coming in contact with the ice blocks 22 will be enabled to pass downwardly, and thence into the storage space through the lower apertures 25 and 26 or their equivalent vertically enlarged aperture, as hereinbefore described.

During the melting of the ice while in said bunkers, and also in said storage spaces, the resulting water will gravitate downwardly through the slatted flooring and upon reaching the upper surface of the bottom wall or floor 1, will eventually find its way into longitudinally extending gutters 32 in and adjacent to the laterally opposite limits in said floor. From said gutters the water can then drain downwardly through outlet pipes 33, which terminate within and below the upper level of cup-shaped traps 34, which cooperate with said pipes to provide a liquid seal, operative to prevent the intake of the much hotter air normally in the region above the railroad track, upon which the car is characteristically mounted and moved. Other types of seals may of course be used as desired. Thus, the water from the melting ice is free to flow from the bottom of the car, but air of any sort and particularly hot air, is purposely and effectively prevented from entering through the said bottom wall or flooring. On the other hand, during cold weather in particular, that is, when the outside temperature is at 32° F., or lower, and during a substantial portion of any trip, the several closures 15 and 20b of the respective bunkers may be opened at such desired angle and in such direction, that the outside air will be drawn into the car during and as a result of the car's movement. Likewise, by proper arrangement of the several closures in opposite directions, the cold outside air may be taken into a bunker at one

end and forced through the car and thence out of the bunker opening at the other end, or out of an intermediate bunker opening, at the other end, or out of an intermediate bunker opening, exactly as desired.

Having described one embodiment of the invention, it is to be understood that the broad principles involved anticipate numerous variations in the details of construction, without departing from the spirit of the invention as set forth in the appended claims, while additional refinements may be added, if desired, as for instance the provision of exterior means of identification for the interior compartments, as for instance the use of such symbols as "A" and "B," which when used upon bills of lading readily denote which compartment is to be opened by a given consignee, and thus precluding the necessity of opening each in order to determine their contents.

Also, it is to be understood that the present invention is equally adapted to automobile trucks and trailers, wherefore the term vehicle is employed to include any devices of this class, which are propelled from place to place either upon railways or highways.

Having thus described my invention, what I claim as new and desire to protect by Letters Patent of the United States is:

1. A refrigerator vehicle, comprising end ice bunkers and an intermediate ice bunker separated by independent storage compartments having independent closure-controlled openings providing access thereto, a false apertured flooring in each of said compartments and a false apertured floor in each of said bunkers, the inner walls of said end bunkers and both walls of said intermediate bunker being provided at their upper extremities with inlet apertures, and adjacent to their lower extremities with outlet apertures both above and below said false floorings.

2. A refrigerator vehicle, comprising end ice bunkers and an intermediate ice bunker separated by independent storage compartments having individual openings for access thereto, the inner walls of said end bunkers and both walls of said intermediate bunker being provided with apertures adjacent to their upper and lower extremities, whereby the circulation of air within

each compartment is independent of that in the other compartment, and the chilling effect of the intermediate bunker bolsters that of the end bunkers independently, a longitudinally extending gutter provided in the floor of each of said compartments, and a drain aperture for said gutter.

3. A refrigerator vehicle, comprising end ice bunkers and an intermediate ice bunker separated by independent storage compartments having independent closure-controlled openings providing access thereto, a false flooring composed of spaced slats in each of said compartments and a false floor composed of spaced slats in each of said bunkers, the inner walls of said end bunkers and both walls of said intermediate bunker being provided at their upper extremities with inlet apertures, and adjacent to their lower extremities with outlet apertures both above and below said false floorings, a longitudinally extending gutter provided in the floor of each of said compartments, and a drain aperture for said gutter.

4. A refrigerator vehicle, comprising an end ice bunker, a second ice bunker within and spaced from the ends of said vehicle to provide independent storage compartments, the walls of said bunkers being built unitarily into the structure of the vehicle as rigid partitions and provided in their upper and lower portions with apertures, independent means of access to said compartments, and a false flooring having spaced apertures, whereby the circulation of air within each compartment is independent of that in the other compartment and flows beneath as well as above objects resting upon said flooring.

5. A refrigerator vehicle, comprising end ice bunkers and an intermediate ice bunker separated by independent storage compartments having independent closure-controlled openings providing access thereto, the walls of said intermediate ice bunker being rigid and forming an integral part of the vehicle structure, a false flooring having apertures in each of said compartments, the inner walls of said end bunkers and both walls of said intermediate bunker being provided adjacent to their upper and lower extremities with air-circulating apertures.

JAMES J. CHIARDIO.
